FIG. 1.

FIG. 3.

FIG. 2.

London C. Kasbaum,
Inventor

By *Geo. P. Kimmel.*

Attorney

UNITED STATES PATENT OFFICE.

LANDON C. KASBAUM, OF LAPORTE, INDIANA.

STREET-INDICATOR FOR CARS.

1,347,545.

Specification of Letters Patent. Patented July 27, 1920.

Application filed October 26, 1916. Serial No. 127,877.

To all whom it may concern:

Be it known that I, LANDON C. KASBAUM, a citizen of the United States, and resident of Laporte, in the county of Laporte and 5 State of Indiana, have invented certain new and useful Improvements in Street-Indicators for Cars, of which the following is a specification.

This invention has reference generally to 10 indicators and more particularly relates to a street indicator especially adapted for use on street cars.

It is the primary aim and object of this 15 invention to provide a housing adapted to be mounted in the front part of a street car for operatively receiving novel street indicating means, means being also mounted in the housing and in connection with the street indicating means for operating the 20 indicating means so as to successively display the names of the streets as the car upon which the device is mounted, approaches the streets, thus informing the passengers within the car of the names of the 25 streets.

It is an equally important object of the 30 present invention to provide novel means for controlling the movement of the operating means so as to consequently insure an efficient operation of the indicating means.

More specifically, the present invention 35 contemplates the provision of a pair of rotatably mounted rollers for receiving the indicating web as well as another roller frictionally engageable with the intermediate portion of the web for moving the web from one roller to the other, manually operable means being incidentally arranged in connection with the roller for partially 40 rotating the operating roller a predetermined distance.

Still further, the invention has to provide 45 means for holding the web in frictional engagement with the operating roller to facilitate the movement of the web.

Among the other aims and objects of the 50 present invention may be recited the provision of a device of the character mentioned with a view to compactness and in which the number of parts are few, the construction simple, the cost of production low and the efficiency high.

Other improvements and novel details in 55 the construction and arrangement of the parts will be appreciated from the detailed description below, which is to be read in

connection with the accompanying drawings forming a part thereof, wherein I disclose a preferred embodiment of the invention for the purpose of illustration.

60

The invention is clearly illustrated in the accompanying drawings in which:

Figure 1 is a longitudinal section through the housing showing the invention proper in side elevation.

65

Fig. 2 is a horizontal section through the housing showing the invention proper in top plan.

70

Fig. 3 is a side elevational detail of the controlling means for the operating roller.

Similar characters of reference are employed in all of the above described views, to indicate corresponding parts.

75

Referring now, more particularly, to the accompanying drawings, I provide a housing 1, which may be and preferably is of a rectangular configuration being provided with a sight-opening 2, in the front end thereof. This housing is adapted to be mounted in the front end of a car in such a 80 position as to be within the view of the passengers. Mounted adjacent top and bottom of the housing and transversely of the sides are a pair of shafts 3, while rollers 4 and 5, are rotatably mounted on the shafts the upper roller 5 having a resilient action for a purpose that will presently appear. An indicating web 6, is connected to the lower roller 4 at one end while the opposite end is connected to the roller 5. This web as is 85 apparent upon reference to the drawing is windable about the rollers and is also provided throughout its length and transversely thereof with the names of streets in the order in which the car approaches them.

90

With a view toward maintaining a portion of the web directly behind the sight opening 2 and also to provide means for operating or moving the web from the roller 4 to the roller 5, I have rotatably mounted another shaft 7, transversely of the housing and in the sides thereof adjacent the forward end. A large roller 8, is carried by this shaft and is maintained in frictional engagement with the inner or 100 rear surface of the web and when the roller 8 is partially rotated the web will be moved a short distance in a corresponding direction. Friction rollers 9, are rotatably mounted in suitable brackets 10, above and 105 below the sight 2 and transversely of the housing the rollers being arranged to hold

110

the web in frictional relation with the roller 8 and facilitate the efficient operation thereof.

In order to manually actuate the roller 8 at a predetermined time so as to successively display the names of the streets through the sight opening, I have mounted a bracket 11, on the under surface of the bottom. A lever 12, is fulcrumed intermediate its ends 10 to the lower end of the bracket 11 while a coil spring 13, has its respective ends connected to one end of the lever 12 and to the bottom of the housing for a purpose that will presently appear. A rod 14, has 15 its lower end pivotally connected to the opposite end of the lever 12 and is movably arranged through an opening 15, in the bottom of the housing and terminates at a point approximately in alinement with the plane 20 of the axis of the shaft 7. An arm 16, is connected to the shaft and has the outer end pivotally connected by means of a suitable fastening device 17, to the upper end 25 of the rod 14 while a pawl 18, is also pivotally connected to the upper end of the rod on the side opposite to that upon which the arm is arranged while connection is maintained through the fastening device 17. A ratchet wheel 19, is rigidly mounted on the 30 shaft adjacent the roller 8 while the pawl is yieldingly held in engagement with the teeth of the ratchet wheel by means of a spring 20, connected to the rod 14. A cable 21, is connected to the end of the lever 12 35 to which the spring 13 is connected and is trained about an idler 22, and run to a suitable point on the car (not shown) where it can be conveniently pulled by the conductor to move the lever 12 against the tension of 40 the spring and consequently raise the rod so that the pawl will engage the tooth in the ratchet wheel above the one in which it is positioned whereupon the cable is released and the tension of the spring 13 45 consequently moves the ratchet wheel as well as the shaft and roller 8 so as to move the web and display the next street thereon through the sight opening.

For the purpose of controlling the movement of the operating roller 8 so as to prevent the roller from moving beyond a predetermined distance and thereby insuring an effective operation of the indicating web I have connected a support 23, to the housing 50 while an arm 24, is pivotally connected to the outer end thereof. A roller 25, is rotatably mounted on the outer end of the arm 24 and is yieldably held in engagement with a spur wheel 26, carried by the shaft 55 7, by means of a spring 27, the respective ends of which are connected to the support 23 and the arm 24. It will be noted that there are the same number of teeth on the wheel 26 as there are on the ratchet wheel 60 19 so that when the ratchet wheel is moved

the distance of one tooth by the ratchet it will be prevented from moving farther by the roller 25 which is yieldably held in engagement with the teeth on the spur wheel. This engagement of the roller 25 with the 70 tooth of the wheel 26 however, is not sufficiently strong to prevent the roller being moved a predetermined distance by the operating means therefor.

The operation of the invention may be 75 reviewed as follows:—

Assuming that the car in which the device is mounted has started on its route and that the major portion of the web is wound about the roller 4 the conductor will pull 80 the cable against the tension of the spring 13 and rock the lever 12 which moves the rod 14 upwardly so that the pawl 18 will be engaged on the tooth above the one in which it is engaged whereupon the cable is 85 released and the spring 13 exerts its tension and moves the rod downwardly which raises the pawl to partially rotate the shaft 7. Inasmuch as the roller 8 is carried by this shaft 7 and frictionally associated with the web 6 90 the web will be moved a slight distance so as to display the proper street through the sight opening 2 and thus indicate to the passengers within the car the name of the street at which the car will make its next 95 stop, if necessary. The spring roller 5 will automatically wind the web as the slack occurs in the web between the roller 5 and the roller 8. The spring pressed roller 25 engaged in the spur wheel 26 allows the 100 shaft to move only a predetermined distance so as to insure the efficient operation of the indicating web. As is readily apparent the device can be subsequently actuated in a similar manner to successively display the 105 names of the streets in the order in which they are approached by the car.

Since many changes could be made in the above construction and many apparently widely different embodiments of this invention could be made without departing from the scope thereof, it is intended that all matter contained in the above description or shown in the accompanying drawings shall be interpreted as illustrative and not 110 in a limiting sense. It is also to be understood that the language used in the following claim is intended to cover all of the generic and specific features of the invention herein described and all statements of 115 the scope of the invention, which, as a matter of language, might be said to fall therebetween.

Having thus described my invention, what I claim as new and desire to secure by Let 125 ters Patent is:

An indicator of the type described comprising a housing having an opening therein, a web, rollers in the housing for carrying the web, a large roller adjacent the open- 130

ing for receiving the web intermediate the afore mentioned rollers, idler rollers bracketed to the housing above and below the opening and to each side thereof and in line 5 with the upper and lower edges for disposition forward of and bearing against the large roller whereby to smooth out and facilitate movement of the web thereover, a spur wheel on the larger roller, a vertically 10 disposed and vertically movable shaft extending into the housing, an arcuate pawl pivoted to the shaft and engaging the spur

wheel to advance the large roller, and a leaf spring pivoted to the shaft below and in line with the pivot point of the pawl and 15 having a curvature opposite to the curvature of the pawl whereby to positively press the pawl at all times although exerting a smooth and minimum frictional contact upon the pawl for the purpose set forth. 20

In testimony whereof, I affix my signature hereto.

LANDON C. KASBAUM.
